UNITED STATES PATENT OFFICE.

ALBERT OPPENHEIM, OF NEW YORK, N. Y., AND EDWARD CLEARY, OF BRIDGEPORT,
CONNECTICUT, ASSIGNEES TO THE CONNECTICUT WEB AND BUCKLE CO., OF BRIDGE-
PORT, CONNECTICUT, A CORPORATION OF CONNECTICUT.

SUSPENDER CAST-OFF.

981,676.

Specification of Letters Patent. Patented Jan. 17, 1911.

Application filed November 1, 1909. Serial No. 525,650.

To all whom it may concern:

Be it known that we, ALBERT OPPENHEIM and EDWARD CLEARY, citizens of the United States, and residents of the city, county, and 5 State of New York, and Bridgeport, in the county of Fairfield and State of Connecticut, respectively, have invented certain new and useful Improvements in Suspender Cast-Offs, of which the following is a specification.

Our invention relates to improvements in cast-offs for suspender ends and particularly to that form of device wherein a loop and button are used for the detachable connection of the suspender ends to the cord portions, but is obviously equally as well adapted for use upon other forms of garments.

It is the object of the invention to produce a loop which may be detachably and yieldably connected to a stud so as to permit said parts to readily adjust themselves to the various positions assumed by the connecting parts of the suspender, without 25 any liability of becoming disconnected; to provide a novel form of stud member with attached cord run-way, and yieldable plate to yieldably engage the loop when attached in a manner to permit of its adjustment 30 without becoming disconnected; and finally to provide means for also supporting the drawers.

Further objects of the invention will hereinafter appear; and to these ends the invention consists of a device for carrying out the above objects, embodying the features of construction, combination of elements, and arrangements of parts having the general mode of operation, substantially as herein- 40 after fully described and claimed in the specification and as shown in the accompanying sheet of drawings, in which,

Figure 1, shows a front elevation of a suspender and with loop member of cast-off attached. Fig. 2, is a front elevation of the stud member of cast-off, with cords attached for connection to trouser buttons and drawers. Fig. 3, is an edge view of Fig. 1. Fig. 4, is an edge view of Fig. 2, with cords 50 removed. Fig. 5, is a central vertical section through the stud member of the cast-off. Fig. 6, is an edge view of a slightly modified form of stud member of cast-off, and Fig. 7, is a plan view of sheet metal

blank from which the base portion of the 55 stud member is formed.

Referring in detail to the characters of reference marked upon the drawings, 10 indicates the end of the suspender web, 11 a link attached thereto and 12 the loop portion of the cast-off attached to the said link. This loop is preferably formed of sheet metal 60 and provided with the usual opening 13 comprising a large upper portion, a smaller socket portion and an intermediate contracted throat portion 14. The lower end 65 of the loop is cut across as at 15 thus separating the two side members of the loop at the lower end to permit the same to yield slightly when the stud is drawn through the 70 throat of the loop.

The stud member of the cast-off is formed in part of a sheet metal base piece 15^a which is first blanked out as shown in Fig. 7, and then formed up into the shape indicated in 75 Figs. 2, 4, 5 and 6. The rear end of the stud 16 is riveted to the back of the base plate 15^a as indicated in the drawings, while the opposite end is enlarged to form a head 17 to better engage the loop. The base plate 80 is deflected down, rearward and returned to form a loop 18 which serves as an oval runway for the cord ends 24. The front portion 19 of the base plate is made to spring back and is provided with a hole through 85 which the shank of the stud freely extends and whereby said plate can freely move longitudinally upon said shank when pressure is brought to bear thereagainst. Lugs 20 are turned in from the upper portion of the 90 back of the base plate to form stops against which the front plate will strike when sprung in, as in the attachment to the loop of the stud and for the purpose of affording a resistance to the loop when shoved there- 95 under. This stop may be formed integral with the back plate as shown in the preferred figures of the drawings or may be obtained by attaching a separate ring around the stud and which may be formed of rubber or metal as by 21 in Fig. 6.

A lug 22 is formed in the upper end of the yieldable front plate whereby the stud member is made to strike and is prevented from locking into the upper edge 23 of the 105 loop member when the parts are being separated thus insuring a quick and convenient detachment of the parts.

The intermediate portion of the cord runway 18 is stamped down to form an eye 25 for the attachment of the metal end 26 of the intermediate drawer supporting 5 cord 27 to the lower end of which also is attached a common form of spring clamp 28 to engage the drawer.

In connecting the two parts of the clamp the larger portion of the loop is laid over 10 the head of the stud and then the loop pressed inward to slightly spring the front plate whereupon said loop is drawn up under the head of the stud so that the contracted throat of the loop engages the sides 15 of the shank of the stud in a way to be slightly sprung apart until the shank is seated within the lower pocket of the loop. The tension of the front spring plate 19 is such as to bear against the underside of the 20 loop when engaged in a way to cause sufficient friction to prevent unnecessary play and detachment of the parts.

Having thus described our invention what we claim and desire to secure by Letters Patent is:—

25

The herein described suspender end cast-off, comprising a loop, a stud for the engagement of the loop, a sheet metal base member to which the stud is fastened and bent around to form an oval cord run-way 30 and disposed up under the head of the stud to form a yieldable front plate to engage the underside of the loop when attached, and a lug formed on the upper end of the spring plate to strike against the upper edge of the 35 loop when disconnecting the parts.

Signed at Bridgeport, in the county of Fairfield, and State of Connecticut this 22nd day of October, A. D., 1909.

ALBERT OPPENHEIM.
EDWARD CLEARY.
